UNITED STATES PATENT OFFICE.

ALBERT MAURER, OF NEW YORK, N. Y.

MEDAL-HOLDER.

1,310,803.

Specification of Letters Patent. Patented July 22, 1919.

Application filed March 14, 1919. Serial No. 282,531.

To all whom it may concern:

Be it known that I, ALBERT MAURER, a citizen of the United States, residing at the city of New York, in the county and State 5 of New York, have invented certain new and useful Improvements in Medal-Holders, of which the following is a specification.

My invention relates to devices for conveniently and detachably securing medals or badges, such as military medals and the like, to the coat or other garment of the wearer. Such medals are commonly secured to a garment by a safety pin which extends through the ribbon carrying the medal. By my invention a device is provided which presents a much more attractive appearance, from which the medal may very readily be removed or on which the medal may easily be positioned, and which does not require that a pin shall be inserted in the garment whenever the medal is to be put on. I accomplish these purposes by the provision of a headed pin which is adapted to be inserted into and frictionally held in a sleeve which is provided with a head or enlargement on its opposite end similar to that on the pin. The sleeve forms a bar on which the loop of the ribbon bearing the medal may be inserted before the pin is slipped into position in the sleeve, the sleeve with the pin therein being held against the garment of the wearer by holding devices which comprise loops through which the sleeve and pin are inserted. Preferably, these loops are formed on the outer ends of short pins which may be inserted through the garment, these pins having their inner ends threaded, or other arrangement made for securing holding devices to their inner ends after they have been inserted through the garment. Preferably, the holding means for the pins referred to take the form of metallic disks having threaded openings therein in which the short pins are screwed, these disks also preferably having serrations which are adapted to bear against the inner surface of the garment, and also having flanges which are directed inwardly to protect the person of the wearer against the points of the pins.

In order that my invention may be more clearly understood, attention is hereby directed to the accompanying drawings forming part of this application and illustrating the preferred embodiment of my invention.

In the drawings Figure 1 represents a front elevation of my device bearing a medal and

applied to a coat; Fig. 2 is a front elevation of the device as assembled, the garment and ribbon not being shown; Fig. 3 is a horizontal section taken on line 3—3 of Fig. 2, 60 the garment, however, being shown; and Fig. 4 is a cross section taken on line 4—4 of Fig. 3.

Referring to the drawings the medal holder comprises a sleeve 1 having enlargement 2 of cylindrical or other desired shape at one end; the pin 3 is adapted to slidably engage within sleeve 1 and to be frictionally held therein. This pin is provided with a head or enlargement 4 at its end similar to 70 the enlargement 2 at the opposite end of the sleeve.

The sleeve 1 with the pin 3 therein forms a bar on which the ribbon 5 carrying the medal or badge 6 is adapted to be secured. 75 The sleeve 1 is secured to the coat or other garment 7 by means of loop 8, 8.

Loops 8, 8, are preferably formed on the outer ends of pins 9, 9, which are adapted to be inserted through the garment at suitable 80 points and to be detachably held in such positions. As shown, the pins 9, 9, are preferably provided with screw-threads 10 adjacent their inner ends and holding devices 11, 11, are provided for coöperation with 85 the inner ends of these pins. Preferably, the devices 11, 11, take the form of small disks or cups having threaded openings at their centers through which the pins 9, 9, are screwed. These devices are preferably provided with outwardly extending peripheral serrations 12 which are adapted to take hold of the inner surface of the garment to hold the same firmly in position. Devices 11 are also preferably formed in cup shape so as to 90 present inwardly extending peripheral flanges 13. These are for the purpose of guarding the person of the wearer from the inner, more or less pointed ends of pins 9. When the pins 9, for example, are inserted 100 through a layer of a coat with the sleeve 1 and pin 3 on the outer surface thereof, the devices 11 will be positioned against the inner surface of the cloth with the inner edge of each flange 13 bearing against the vest 105 or other inner garment of the wearer, the inner ends of the pins 9 being contained within the cups thus formed so that the points of pins 9 cannot press against the surface of the inner garment.

When the medal holder is to be used, the pins 9 are extened inwardly through the gar-

ment 7 and secured in position by screwing the holding devices 11 on their inner ends as stated. The loops 8 will then be the only portions of the device visible, when the 5 medal is not being worn, and as these loops are inconspicuous the effect is not objectionable. When the medal is to be attached, the sleeve 1 may be passed through one of the metal loops or eyes 8, and the ribbon of the 10 medal slipped over the same. The pin 3 is passed through the other loop or eye 8 and pressed into position within the sleeve 1, both of the loops or eyes 8 then bearing slidably on the sleeve 1 and the end of the 15 sleeve 1 resting in contact with the head 4 on the pin 3. The medal may be taken off by simply pulling outwardly on the heads 2 and 4 of the sleeve and pin to separate the sleeve from the pin, after which the short 20 pins 9 may be removed or left in position in the garment as desired.

What I claim is:—

1. In a medal holder, the combination of a sleeve having an enlarged end, a headed 25 pin, adapted to slidably fit in said sleeve and to be frictionally held therein, and means adapted to be detachably secured to a garment, having loops through which said sleeve and pin may be removably inserted, 30 for detachably securing said sleeve and inclosed pin to the garment.

2. In a medal holder, the combination of ribbon-holding means, comprising a bar, and having enlarged ends, and means for securing 35 said means to a garment, comprising threaded pins adapted to be inserted through the garment, adjacent the ends of said ribbon-holding means, and holding means having threaded openings in which 40 the inner ends of said threaded pins may be screwed, adapted to bear against the inner surface of the garment.

3. In a medal holder, the combination of a sleeve having an enlarged end, a headed 45 pin, adapted to slidably fit in said sleeve and

to be frictionally held therein, and means for securing said sleeve and pin therein to a garment, comprising pins adapted to be inserted through the garment, having loops on their outer ends through which said sleeve 50 and first named pin may be inserted, and means for removably holding said last named pins in position.

4. In a medal holder, the combination of a sleeve having an enlarged end, a headed 55 pin, adapted to slidably fit in said sleeve and to be frictionally held therein, and means for securing said sleeve and pin therein to a garment, comprising threaded pins adapted to be inserted through the garment, having loops on their outer ends through which 60 said sleeve and first named pin may be inserted, and holding means having threaded openings in which the inner ends of said threaded pins may be screwed, adapted to 65 bear against the inner surface of the garment.

5. In a medal holder, the combination of a sleeve having an enlarged end, a headed 70 pin, adapted to slidably fit in said sleeve and to be frictionally held therein, and means for securing said sleeve and pin therein to a garment, comprising threaded pins adapted to be inserted through the garment, having loops on their outer ends 75 through which said sleeve and first named pin may be inserted, and members in which the inner ends of said threaded pins may be screwed, having serrations adapted to bear against the inner surface of the garment and flanges adapted to guard the wearer against the inner ends of said threaded pins.

This specification signed and witnessed this 12th day of March, 1919.

ALBERT MAURER.
